UNITED STATES PATENT OFFICE

2,117,325

VALVE MECHANISM FOR INTERNAL COMBUSTION ENGINES, COMPRESSORS, AND THE LIKE

Cecil D. Howard, Swarthmore, and Frank R. Maxwell, Rose Valley, Pa., assignors to Sun Shipbuilding and Dry Dock Company, Chester, Pa., a corporation of Pennsylvania

Application August 12, 1936, Serial No. 95,702

2 Claims. (Cl. 230—222)

This invention relates to an improvement in valve mechanism for internal combustion engines, compressors and the like.

Valve mechanism in accordance with this invention will be found to possess great advantage over valve mechanism, generally of the poppet type, heretofore used in internal combustion engines, compressors and the like, in that it will be positively driven, with avoidance of cams, springs, and the like, thus avoiding limitations on speed, in that it will be quiet and efficient in operation and in that it will be safe and long lived due to the fact that its various parts may be made relatively heavy without reducing its efficiency or speed of operation.

Valve mechanism in accordance with this invention will lend itself to use with high efficiency in connection with the control of the scavenging air in two cycle engines of the fuel injection or Diesel type, in that its use in such engines will enable their operation at higher speeds than heretofore, with consequent increase in their capacity. However, it will be understood that the mechanism in accordance with the invention will lend itself to use in Diesel engines of the four cycle type and also in internal combustion engines generally and in compressors and the like.

Having now indicated, in a general way, the nature and purpose of this invention, we will proceed to describe a preferred embodiment thereof with reference to the accompanying drawings, in which:

Figure 1 is a sectional view, partly broken away, of an engine equipped with valve mechanism in accordance with this invention.

Figure 2 is a view, partly in section and partly diagrammatic, illustrative of a cycle of operation of the valve mechanism shown in Figure 1.

Figure 3 is a sectional view showing a modification of the valve mechanism shown in Figure 1.

Figure 4 is a plan view of the subject of Figure 3.

Figure 5 is a sectional view of a double acting engine equipped with valve mechanism in accordance with this invention.

Figure 6 is a sectional view on lines 6—6, Figure 5.

Figure 7 is a plan view, partly in section, looking in the direction of the arrow, Figure 5.

With reference to the several figures, this invention will be described as adapted to an engine of the two cycle Diesel type. However, it will be understood that, as has been indicated, it is adaptable to engines, compressors, and the like, of various other types.

Referring more particularly to Figures 1 and 2, 1 indicates an engine base on which is mounted in suitable bearings a crank shaft 2. A connecting rod 3 is secured to the crank shaft and to a piston 4 in a working cylinder 5. A suitable fuel injection device, not shown, is provided for the admission of fuel to the cylinder 5.

The working cylinder 5 is provided with exhaust ports 6, communicating with an exhaust passage 7. The working cylinder is provided with cooling jackets 8.

Opening in the head of the cylinder 5, is a valve cylinder 9, provided with ports 10, affording communication between the working cylinder 5 and a scavenging air passage 18, adapted to be controlled by means of a slide or piston valve 11.

Pivotedly connected to the piston valve 11 and to a rocker arm 12 on a suitably mounted fulcrum pin 13 is a link 14, while a connecting rod 15 is also connected to the rocker arm and to a crank 16 on a driven shaft 17. Shaft 17 is driven through any suitable means from the crank shaft 2.

As will be especially noted, the link 14, pivotally connected to the piston valve 11 and to the rocker arm 12, forms, with the rocker arm 12, a toggle, through which the piston valve 11 is reciprocated in the cylinder 9 from the driven shaft 17, through the connecting rod 15.

The driven shaft 17, by which the piston valve 11 is operated through the toggle, may be driven by any suitable form of connection from the crank shaft 2 of the engine, and will be driven, in the case of a two cycle engine, at engine speed, or, in the case of a four cycle engine, at half engine speed.

For operation of the engine above described, the rocker arm 12, when actuated by the rod 15, will be oscillated about the pin 13, thus causing the pin 19, by which the arm 12 and link 14 are connected, to move on an arc between the points A and B, while the pin 20, connecting the rod 15 to the arm 12, moves on an arc from the points a to b.

Thus, when the pin 20 is in its position b, the pin 19 will be in its position B, the piston valve 11 will be at the outer end of its stroke with the port 10 closed and the toggle, formed by the arm 12 and link 14, will be straight, or approximately straight. The mechanism will be in such position when the pressure in the cylinder 5 is at its highest; i. e. on burning of the charge in cylinder 5, and as a consequence the heavy thrust on the piston valve 11 will be taken by the link 14, pin 55

19, arm 12 and pin 13, without load on the pin 20 and connecting rod 15.

From the position *b* the pin 20 will move toward the position *a* and cause the pin 19 to move from the position *B* toward the position *A*, which results in upward travel of the piston valve 11 in cylinder 9. The initial movement of the piston valve; i. e. from lower dead center, at which the piston pin will be at a point *E* to just closing the ports 10, at which the piston pin will be at a point *F*, will be very slow while the pressure on valve 11 is still high and hence a low load is imposed on the pin 20 and connecting rod 15. The movement speeds up as it continues, but the pressure in cylinder 5 rapidly drops and as a consequence the loads on pin 20 and rod 15 remain low. In the continued movement of the pin 20 toward *a* and of the pin 19 toward *A*, the valve ports 10 are opened and since the rate of movement of the pins 19 and 20 in that portion of the arcs *AB* and *ab*, in which the ports are opened, is rapid and consequently the rate of movement of the valve 11 from point *F* to point *G* is rapid, the ports 10 will be opened rapidly and as a consequence may be relatively large without requiring a long valve stroke.

Referring now more particularly to Figure 2, it will be noted that the toggle, as diagrammed, bends slightly with the points *b*, *B* slightly out of line when the piston valve is in lower dead center position; i. e. with the piston pin at the point *E*. With such arrangement little of the resistance of the toggle is lost, but the period of slow movement of the toggle and of the piston valve is increased.

By Figure 2 the angular movement of the crank 16 between points *a'*, *b'* and *c'* and the angle of movement of crank *c* between the points *a'*, *b'*, and *c'*, corresponding to the points *a*, *b* and *c* on the arc of movement of pin 20, are indicated. It will be noted from an inspection of Figure 2 that the toggle and connecting rod 15 are so proportioned and arranged with respect to the piston valve 11 that the crank 16 in rotating 45 through an arc of about 107° from *c'* to *c''* through *a'* and in rotating in an arc of about 253° from *c''* to *c'* through *b'* will cause a very slow movement of the piston valve during the period of its closure of the port and a very rapid opening and closing movement.

It will be appreciated that the movement of the piston valve 11 and the subsequent opening and closing of the ports 10 for the admission and cutting off of scavenging air is timed with reference to the cycle of operation of the engine. The correct timing is effected by arranging the driving connection as, for example, gears, between the crank shaft 2 and the driven shaft 17 so that the rotation of the two shafts is in the proper angular relationship. In application to a four cycle engine, it will be appreciated that a pair of valves, one controlling inlet and the other exhaust, will be appropriately timed.

Referring now to Figures 3 and 4, a single working cylinder 5 may be provided with a plurality of piston valves 11 arranged in a circle about the cylinder head as indicated in Figure 4 and a plurality of the valves may be driven from a driven shaft 17 through a single crank pin 21 and connecting rod 15. In such arrangement the several rocker arms 12, elements of the toggles, are provided with extensions 12', which are respectively connected to a link 22, the several fulcrum pins 13 are mounted in suitably supported bearings 24 and the connected toggles are actuated for

reciprocation of the several piston valves by the connection of the connecting rod 15 to an extension 23 on one of the rocker arms 12.

The operation of the mechanism as shown in Figures 3 and 4 is as described above with reference to Figure 1.

Referring now to Figures 5, 6 and 7, the cylinder 25 is provided with water jackets 26 and a centrally located exhaust port 27. The cylinder is provided at its opposite ends with cylinder heads 30. Within the cylinder 25 is a piston 28, to which is secured a connecting rod 29 extending through one of the cylinder heads 30 for connection with the crank shaft. The rod 29 is suitably packed, as with metal packing 31, to prevent leakage from the cylinder. The piston 28, in its reciprocation within the cylinder, is adapted to partially uncover the exhaust port at opposite ends of its stroke.

The cylinder heads 30 are each provided with a pair of cylinders 32, arranged in offset relation as shown in Figures 6 and 7. The cylinders are provided with ports 33 affording communication between the cylinders and conduits 34 for scavenging air. Within the cylinders 32 are piston valves 35 to which are pivotally connected links 36, which in turn are connected to one arm of bell cranks 37, pivotally mounted on suitably supported pins 38.

The bell cranks connected to the pairs of piston valves in the cylinder rods, respectively, are connected by means of a link 39. Connecting rods 40 are connected to a third arm on one of the bell cranks 37, associated with the pairs of valves in the cylinder heads, respectively, and to a crank 41 on a shaft 42, driven in any suitable manner from the crank shaft of the engine.

The operation of the engine illustrated in Figures 5, 6 and 7 will, it is believed, be obvious, it being noted that for purposes of illustration the engine shown is of the double acting Diesel type. The piston valves controlling the admission of scavenging air to the cylinder 25 will be operated from the crank shaft of the engine at engine speed in the case of the engine illustrated through the medium of the crank shaft 42, rods 40 and the bell cranks 37 connected by links 39. It will be noted that the links 36 and the arms of the bell cranks to which they are connected will form a toggle, as do the link 14 and rocker arm 12 of the engine shown in Figure 1.

The toggles formed by the links 36 and the arms of the bell cranks 37 to which they are connected, may be arranged as in the case of the similar mechanism shown in Figure 1 to assume a straightened out position when the piston valves are at their lower dead centers or may be arranged to break slightly backward when the piston valves are in such position, all as more fully explained with reference to Figures 1 and 2. Likewise, it will, of course, be understood that the operation of the valves will be suitably timed with the operation of the piston 28.

It will be noted that the cylinders 32 in the cylinder heads 30 are arranged in offset position and also that the cylinders extend at an angle to the axis of the working cylinder 25. By virtue of such arrangement, scavenging air enters the cylinder 25 in streams traveling generally in opposite direction and also at an angle to the axis of the cylinder 25, with the result that the scavenging air is given a rotary, swirling motion in its passage to the exhaust port and operates in a highly efficient manner to thoroughly clean burnt gases from the cylinder.

It will be understood that the above description of mechanism in accordance with this invention is for the purpose of illustration only and it will be appreciated that various modifications in detail may be made without departing from the scope of the invention.

What we claim and desire to protect by Letters Patent is:

- 5 1. In an internal combustion engine, in combination, a working cylinder, a working piston in said cylinder, a crank shaft, means connecting said working piston with said crank shaft, a passage communicating with the interior of the cylinder, a reciprocable piston valve adapted for the control of said passage, a second crank shaft, means affording a connection between said valve and said second crank shaft including a toggle extending between and pivotally connected to said valve and a fixed pivot and a connecting rod connecting said second crank shaft with said toggle at a point adjacent to the fixed pivot, and means connecting said two crank shafts whereby said second crank shaft is rotated to effect reciprocation of said valve through said connecting rod and toggle, the toggle and said connecting rod connecting said second crank shaft with the toggle being so proportioned and arranged that in the rotation of the second crank shaft through an

arc of about 253° the said piston valve will move relatively slowly and so that in the rotation of the second crank shaft through an arc of about 107° the piston valve will move relatively rapidly.

2. In an internal combustion engine, in combination, a working cylinder, a working piston in said cylinder, a crank shaft, means connecting said working piston with said crank shaft, a passage communicating with the interior of the cylinder, a reciprocable valve adapted for the control of said passage, means affording a connection between said valve and said crank shaft including a toggle extending between and pivotally connected to said valve and a fixed pivot and a connecting rod connected with said toggle at a point adjacent to the fixed pivot, and means for actuating said connecting rod to effect reciprocation of said valve through said toggle, the toggle and said connecting rod and the means for actuating said connecting rod being so proportioned and arranged that in the rotation of the crank shaft through an arc of about 253° the said valve will move relatively slowly and so that in the rotation of the crank shaft through an arc of about 107° the valve will move relatively rapidly.

CECIL D. HOWARD.

FRANK R. MAXWELL.
